UNITED STATES PATENT OFFICE.

LAUREN M. FITCH, OF ROME, NEW YORK, ASSIGNOR OF ONE-HALF TO
MOSES M. DAVIS, OF SAME PLACE.

CARRIAGE RUNNING-GEAR.

SPECIFICATION forming part of Letters Patent No. 417,317, dated December 17, 1889.

Application filed October 2, 1889. Serial No. 325,794. (No model.)

To all whom it may concern:

Be it known that I, LAUREN M. FITCH, of Rome, in the county of Oneida and State of New York, have invented certain new and useful Improvements in Carriage Running-Gear; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in carriage or buggy springs and running-gears, and particular features of construction.

In the drawings which accompany and form part of this specification, and in which similar letters and figures of reference refer to like parts in the several figures, Figure 1 shows a perspective top view of the springs and running-gear. Fig. 2 shows an edge view of the same. Fig. 3^a shows a central section of the front axle-tree and cap and bolster-bar and a cross-section of the same and top view of a clip shown therein. Fig. 3^b shows an edge view of what I term a modified form of construction of the Y-shaped head-piece of the spring-braces. Fig. 4 shows a top, edge, and bottom view of a supporter-piece. Fig. 5 shows a modified form of the device shown in Fig. 4. Fig. 6 shows a top view of the Y-shaped head-piece. Fig. 7 shows a top view of part shown in Fig. 3^b.

Referring more specifically to the reference-numerals of the drawings, 1 indicates the rear axle, 2 the forward axle, and 8 the front bolster-bar.

3^a are the main supporting-springs, clipped or secured to the rear axle and to the front bolster-bar 8. Pieces 4 are provided, secured to the under side of springs 3 by clips 5 or other suitable means. Pieces 4 are constructed as rights and lefts and are provided with a projection 6, which extends inside of the springs 3, upon which the body (not shown) rests, and to which it is secured. Pieces 4 are also provided on their under sides with a projecting lug 7. Pieces 4 are secured to the springs substantially in the middle. Rear spring brace and draw bars

9 are provided, clipped or otherwise suitably secured to the rear axle near the wheel-bearing, and pass to the lugs 7, secured on the under side of the spring, and 55 preferably to the outside of the lug, where they terminate in an eye. Front spring brace and draw bars 10 extend from the lug 7, and preferably the inside thereof, to the Y-shaped head-piece 11, and are secured thereto by 60 bolts passing through the overlapping ends of each, as shown in Figs. 1, 2, and 3^a, or by an eye upon the bar and ears upon each branch of the Y-shaped head-piece, and a bolt passing through both, as shown in Figs. 3^b 65 and 7. The lug 7 upon the piece 4 is preferably at an angle to the line of the spring, so that the bars 9 and 10 will fit nicely thereto without binding. Bars 9 and 10 are secured to the lug 7 by a bolt 12, passing 70 through the eye on the end of each, and a hole in the lug.

A bar 13 is provided, passing from spring to spring and secured to each spring 3 by a clip or other suitable contrivance. The bar 75 13, in connection with projections 6, supports the body; or I dispense with the bar 13 and use the supporter-piece shown in Fig. 4, in which case the body rests upon projections 6 and 14 and is bolted thereto. 80

The axle-cap is indicated by 16 and moves with axle 2.

15 is a clip which secures the bolster-bar 8 to the front axle, the two arms of which pass through openings *a* and *b* of the Y-shaped 85 head-piece, and are provided with screw-threads and a nut above and one below the Y-shaped head-piece. Clip 15 may also be provided with a central prong, which passes through the bolster-bar, the friction-plates 90 between the bolster-bar and axle-cap, the axle, and the opening *c* through the Y-shaped head-piece, and furnishes a pivot for the turning of axle and axle-cap between the bolster-bar and Y-shaped head-piece. 95

It is evident that other changes and modifications from those mentioned may be made in the construction without departing from principles or equivalents of my invention.

What I claim as new, and desire to secure 100 by Letters Patent, is—

1. In a running-gear, the combination of

the rear and front axles, the pivoted bolster-bar, the pair of supporting-springs secured at one end to the rear axle and at each other to the bolster-bar, the supporting-piece 5 secured to the under side of the central portion of each of the springs, and having a downwardly-projecting perforated ear directly under the spring, and the inwardly-extending projection adapted to support the 10 body, and the draw or brace bars secured to the rear axle adjacent to the wheel-bearing and extending to and pivoted to the ear, and the forward draw or brace bars pivoted to the ear and extending to and pivoted centrally 15 to the front axle, substantially as set forth.

2. In a running-gear, the combination of the rear and front axles, the bolster-bar pivoted to the front axle, the supporting-springs 20 secured at one end to the rear axle and at the other to the bolster-bar, the body supporter-piece secured to the middle portion of each spring on the under side and having a projecting portion extending inwardly and adapted to support the vehicle-body, and having a downwardly-projecting perforated lug directly under the springs and at an angle to the spring and substantially in line with a line drawn from the rear axle adjacent 25 to the wheel-bearing to the central portion of the front axle, the brace-bars secured to the rear axle adjacent to the wheel-bearing and extending to and pivoted to the lug, and the brace-bars extending from the lugs 30 to and pivoted to the central portion of the front axle-tree, substantially as set forth.

3. The combination, in a running-gear, of the front and rear axles, the bolster-bar pivoted to the front axle, the supporting-springs 40 extending from the rear axle to the bolster-bar and secured to each, the independent piece secured to the middle portion of each of the springs having a downwardly-projecting perforated lug directly under the spring 45 at an angle to the spring and substantially

in line with a line drawn from the rear axle adjacent to the wheel-bearing to the central portion of the front axle, the brace-bar secured to the rear axle adjacent to the wheel-bearing and extending to one side of the perforated lug, the brace-bar extending from the lug to the central portion of the front axle-tree and pivoted thereto, and the bolt passing through perforations or eyes in the ends of the brace-bars and the perforation in the lug, substantially as set forth. 50 55

4. The combination, in a running-gear, of the front and rear axles, the bolster-bar pivoted to the front axle, the body-supporting springs extending from the rear axle to the front 60 front bolster-bar and secured to each, the supporter-pieces secured to the under side and middle portion of the springs having an inwardly-extending projection adapted to support the body, and the downwardly-projecting perforated lug directly under the 65 spring and at an acute angle to the spring and substantially in line with a line drawn from the rear axle adjacent to the wheel-bearing to the middle portion of the front 70 axle, the brace-bars secured to the rear axle adjacent to the wheel-bearing and extending to the lug on the under side of the spring, the Y-shaped head-piece 11, the clip 15, spanning the front bolster-bar and axle and secured to the Y-shaped piece 11 thereto, and the brace-bars extending from the lug on the under side of the spring to the Y-shaped head-piece and secured thereto, and the bolts 12, 75 passing through eyes in the end of the brace- 80 rods and the perforation in the lug on the under side of the spring, combined and used substantially as set forth.

In witness whereof I have affixed my signature in presence of two witnesses.

LAUREN M. FITCH.
